(57) **CLAIM**

The ornamental design for a protective case for wireless tracking device, as shown and described.

DESCRIPTION

FIG. 1 is a front, right, and top perspective view of a protective case for wireless tracking device, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a cross-sectional view of the protective case for wireless tracking device of FIG. 6, taken along section line 8-8.
